BABY WALKER AND ANCHOR

Carl B. Dahlberg, Alhambra, Calif., assignor to Hemet Aircraft Corporation, Alhambra, Calif., a corporation of California

Application January 4, 1954, Serial No. 401,969

2 Claims. (Cl. 155—23)

This invention relates to improvements in baby walkers, and particularly that type of baby walker which is designed to have one of its wheels anchored so that the mentioned wheel will be held against rolling rotation and consequently movement of the walker is restricted to a circular path about the anchor as a center.

A primary object of the invention is to provide a novel, simple anchoring means that can be positioned either on a rug or carpeting or on a smooth highly polished surface, such as a waxed floor, and which will effectively restrict the baby walker to movements about the anchor as a center. By having the anchor detachable from the walker the walker may be optionally used either as a conventional walker wherein movements of the walker on its wheels are in no way confined or restricted or upon application of the anchor movements of the walker may be restricted to a circular path.

Another object of the invention is to provide an improved and highly simplified frame construction for baby walkers which will enable the walker to be easily and quickly knocked down or disassembled for shipment or storage purposes and which will also enable the walker to be easily and quickly set up for use. The improved frame construction is such that the parts thereof are relatively few in number and can be easily manufactured and assembled.

With the foregoing and other objects in view, which will be made manifest in the following detailed description and specifically pointed out in the appended claims, reference is had to the accompanying drawings for an illustrative embodiment of the invention, wherein:

Figure 1 is a top plan view of a baby walker embodying the present invention;

Fig. 2 is a view in side elevation of the same;

Fig. 3 is a vertical section on an enlarged scale taken substantially upon the line 3—3 upon Fig. 2, in the direction indicated;

Fig. 4 is a sectional view taken substantially upon the line 4—4 upon Fig. 2 in the direction indicated;

Fig. 5 is a partial view in vertical section taken substantially upon the line 5—5 upon Fig. 2; and

Fig. 6 is a sectional view taken substantially upon the line 6—6 upon Fig. 2.

Referring to the accompanying drawings wherein similar reference characters designate similar parts throughout, the frame of the improved baby walker consists essentially of four parts. One of these parts is of general U-shaped configuration and is preferably formed of metallic tubing. This part has a transversely extending rear portion indicated at 10, see Fig. 4, the ends of which are bent upwardly and forwardly to provide attaching portions 11 at both sides of the walker. From the attaching portions the sides of the U-shaped member diverge forwardly and are bent to extend downwardly and forwardly as indicated at 12 and 13. The extreme ends are bent downwardly as at 14 and are equipped with caster wheels 15. There are two side members, each of which is bent to provide a downwardly and rearwardly extending leg, the

2

legs being indicated at 16 and 17 and these legs terminate in downwardly extending portions 18 equipped with caster wheels 19.

Forwardly of the legs 16 and 17 the side members provide portions 20 which are parallel to and which lie immediately above the attaching portions 11. These portions are detachably secured to the attaching portions by means of bolts 21 equipped with wing nuts 22 enabling the side members to be readily attached to and detached from the attaching portions of the U-shaped member. The legs of the side members extend upwardly and forwardly above the forward legs 12 and 13 as indicated at 23 and are then reversely bent as at 24 to provide combined armrests 25 and seat suspending portions. The rear ends of these armrests are then bent upwardly to provide backrest supports 26 the tops of which may be closed as by plugs 27.

A transverse bar 28 connects the armrests 25 adjacent their forward ends and is attached thereto by means of screws 30 which extend through the armrests into the ends 20 of the bar. The transverse bar 28 cooperates with the transverse portion 10 in holding the two sides of the frame rigidly connected but spaced from each other.

A fabric seat is provided consisting of a bottom 31 having upwardly extending sides 32 and 33. The tops of these sides are hemmed and may be slipped downwardly over the backrest supports 26 and onto the armrests 25. At the forward edge of the seat there is a crotch strap 34 which extends upwardly and which is looped over the transverse tubular member 28. This loop is detachably secured about the tubular member 28 such as by separable fasteners 35. At the back of the seat or bottom 31 there is a backrest 36 which extends upwardly and has loops or hems 37 which can be telescoped downwardly over the upper ends of the backrest supports 26. The tops of these hems or loops are closed so that the backrest is, in effect, suspended from the tops of the backrest supports 26.

A feature of the improved baby walker resides in the means for detachably anchoring one of the caster wheels so that optionally the baby walker may be confined to movements in a circular path or on removal of the anchor, the baby walker may have unconfined movement. To this end the caster wheels are provided with radial recesses 38. The anchoring means consists of a disc 39 adapted to be positioned beneath a caster wheel and which is preferably provided on its underside with a layer of rubber 40 so that the anchor will not slip or slide on polished surfaces, such as waxed floors. On the disc there is an upstanding pin 41 which is receivable in the radial recess 38 in any of the caster wheels. When the anchored disc is beneath a caster wheel and its pin 41 is fitted in the radial aperture 38 therein the pin functions as a means for preventing rolling rotation of the caster wheel although it permits the caster wheel to pivot relatively thereto about the pin 41 as a center. When the anchor is in position as illustrated in Fig. 1, due to the fact that the wheel of the caster wheel cannot rotate, movements of the baby walker are confined to a circular path about the pin 41 as a center. Thus, the baby walker may move from the full-line position shown in Fig. 1 to and through the dotted line position shown therein. In this manner when the anchor is applied the infant's movements in the baby walker may be relatively restricted. On the other hand, it is possible to readily remove and detach the anchor disc from the baby walker, in which case all of the wheels of the caster wheels are free to rollingly rotate. Under these circumstances, the baby walker is unrestricted or unconfined in its movements.

It will be appreciated that the anchor disc can be easily and quickly applied or removed as desired, and that it is unnecessary to fill the anchor disc with any fluid or weighty material. At the same time, when the anchor

disc is in applied position it functions to restrict movements of the baby walker even though the anchor disc is on a highly polished surface or is on a soft resilient surface, such as that afforded by rugs or carpeting.

When it is desired to knock down the baby walker for purposes of shipment or storage, it is merely necessary to loosen the wing nuts 22 and remove the same, in which case the front legs may be detached from the side members as a unit. On removal of the screws 31 the transverse tubular member 28 can be removed and the two side members can be collapsed together in side by side relationship. In this manner the baby walker can be collapsed into a relatively small compact space for shipment and storage purposes. When it is desired to set up the baby walker it is merely necessary to re-apply the transverse tubular member 28 and drive the screws 30 after which the U-shaped member which provides the front legs may be attached by reapplying the wing nuts 22 to the bolts 21.

It will be appreciated from the above-described construction that the improved baby walker can be easily, quickly, and inexpensively manufactured and assembled and that its construction is sufficiently light so that it may be easily propelled by relatively weak infants. Whenever it is desired to restrict the movements of the walker to a circular path, this is accomplished by the application of the anchor disc 39 which can be applied to any one of the four caster wheels.

Various changes may be made in the details of construction without departing from the spirit and scope of the invention as defined by the appended claims.

I claim:

1. A device of the class described comprising a means providing a legged chair, caster wheels on the legs of the chair, and an anchor detachably connected to one of the caster wheels, said anchor comprising a disc having a vertical pin receivable in a recess in one of the caster wheels.
2. A device of the class described comprising a means providing a legged chair, caster wheels on the legs of the chair, an anchor detachably connected to one of the caster wheels, said anchor comprising a disc adapted to be positioned beneath the caster wheel, and an upright pin on the disc receivable in a radial recess in the caster wheel.
